UNITED STATES PATENT OFFICE.

CHARLES E. ALLEN, OF NORTH ADAMS, MASSACHUSETTS, ASSIGNOR OF
ONE-HALF TO IRA J. MEAGLEY, OF BINGHAMTON, NEW YORK.

CIRCUIT FOR TELEPHONE APPARATUS.

SPECIFICATION forming part of Letters Patent No. 290,307, dated December 18, 1883.

Application filed May 5, 1883. (No model.)

To all whom it may concern:

Be it known that I, CHARLES E. ALLEN, a citizen of the United States, residing at North Adams, in the county of Berkshire and State 5 of Massachusetts, have invented certain new and useful Improvements in Circuits for Telephone Apparatus, of which the following is a specification, reference being had therein to the accompanying drawings.

10 My present invention is an improvement in circuits for electrical apparatus. It consists, essentially, of a main-line circuit arranged with reference to central offices of an extended exchange system, which offices 15 have each several local circuits branching therefrom and returning thereto, in which are several subscribers' instruments, arranged in such a way that a circuit may be made up from ground of any one individual station, or 20 any local in any central office of an exchange, to the ground of any desired individual station of any line in any of the central offices from parts of return portions of said locals and main line in which the telephones and 25 transmitters of the stations may be thrown in for conversation, the leading portions (in which are the controlling-magnets of the signaling devices) being temporarily cut off from their return portions, thereby relieving the 30 circuit to be talked through of much resistance.

I have been for some time engaged in experimenting upon the present system of telephoning, and have succeeded in producing a telephone-exchange system consisting of an 35 automatic central office and certain improvements in signal-boxes, so constructed and located with reference to a system of circuits that in their use any subscriber in the exchange can, by the manipulation of his signal-box, ring the bell of any other subscriber and 40 place himself in independent telephonic connection with him without the aid of any one at the central office, and without ringing the bells of other subscribers. The system referred to is not limited in its results to a single exchange and the offices and subscribers 45 associated therewith, but it is calculated to embrace two or more exchanges located upon a main-line circuit, so that an individual sub-

scriber in any of the exchanges may signal 50 and communicate with any other subscriber in his or any other exchange connected with said main line secretly and independently of all stations except the two intended to be engaged.

I mention the foregoing to premise the relation of my present application to several others that will be filed in the Patent Office hereafter, and show or foreshadow the object of this my present application.

As this application relates to the system of 60 circuits in which my central-office machines and signal-boxes are to be placed, I have omitted to show or describe said apparatus at this time; but, in order to illustrate the subject of the present claims, I have shown in my 65 several diagrams the ordinary cross-bar-plug switch-boards and the ordinary switch-connections, and at each individual station I have represented the ordinary electric-vibrating bell and the well-known hand-switches and 70 press-keys.

In my drawings, composed of three sheets, I show on each a switch-board, several individual stations, and their relation to the circuits which form the subject of this application. The several sheets, when connected as 75 hereinafter described, are intended to fully illustrate the gist of the present application.

Referring to the drawings, we may understand, for purposes of illustration, that the 80 three exchanges represented by the capitals "W." "B." "P." are respectively Washington, Baltimore, and Philadelphia. At the Washington central office is a heavy battery, A, for the main line, one side of which is grounded, 85 and the circuit from the other side runs through relay e^1 , switch b^1 , bar 2^1 , main-line wire out; thence to main-line wire on Sheet 2, through relay e , switch b , switch-bar 2^0 , main-line wire, and on to main line shown in Sheet 3; thence 90 through relay e' at "P." central office, switch b^0 , bar 2^0 , main-line return-wire; thence to main-line return-wire of Sheet 2, and thence to main-line return-wire of Sheet 1, terminating on bar 3^0 , leaving the main line normally open. Bar 95 1^0 of the "W." switch-board is in connection with the earth through wire a , switch c^1 , secondary of induction-coil in transmitter b , and

telephone H. Bars 3^b and 3^c in the "B." and "P." centrals are in connection with the return of main line by branches SS'. From the remaining perpendicular bars of each central-office 5 switch-board local circuits extend, one each of which takes in several subscribers' stations, and, returning, each of said circuits occupies two bars of the switch-board, as shown, the exit-wires being connected to local batteries. 10 The wires not connected to batteries are the return-wires of the circuits. All of the local circuits are similar, and one of them, starting and terminating with a central office, may be described as follows: One pole of battery A', 15 which has its opposite pole grounded, runs through annunciator a, switch b^e, bar 4^a, to local-line wire E, which takes in switches c, relay-magnets m of station C⁴ C⁵, and then returns to central office "W.," terminating on 20 bar 5^a, leaving said local circuit normally open. In its return the said local circuit passes through stations C⁵ C⁴, at either of which it may be grounded through a branch circuit, f, by pressing the spring-key c³, which 25 is normally open, or through the secondary of transmitter T and telephone H by closing switch c², which is also normally open. R is a relay, the lever of which, when a current is through magnet m, closes the bell-circuit, in 30 which battery A⁴ is located, causing the bell I to ring. All the plugs of the switch-board, except that of bar 1^a, are located, ready for use, in the lowest horizontal row of holes. Bar 1^a is normally plugged at its intersection with 35 its corresponding horizontal bar, 1^a^x. Now, let us suppose a subscriber—say C¹⁷ of the "P." exchange—wants a subscriber, C¹¹, of the "B." exchange. The subscriber at C¹⁷ first signals the central office "P." by pressing the key c³ 40 at said station, which completes the circuit of battery A⁴, causing the tag of annunciator a⁶ to drop. He now opens switch c at his station to open the exit portion of the line L⁴, closes the switch c', which completes the battery-circuit at C¹⁷ through the primary wire 45 of the transmitter, then closes switch c² to ground the return of circuit L⁴ through the secondary of the transmitter and telephone, and then puts his telephone to his ear. As soon 50 as the tag of annunciator a⁶ drops, the operator at central office "P." opens switch b¹⁰ and removes the pin in bar 5^a to the next hole above, putting it in connection with horizontal and perpendicular bars 1^a^x 1^c and to ground 55 through the transmitter and telephone of said central office, thereby putting said transmitter and telephone in circuit with those of station C¹⁷, through a portion of the return-circuit of L⁴. The operator of central office "P." 60 now says "Hello" to the individual at station C¹⁷, and the latter responds, telling who he wants to communicate with. The operator at the central office "P." now removes the plug from bar 5^a to next hole above and plugs it in 65 connection with horizontal bar 2^a^x, and then opens switch c⁴ of central transmitter and re-

moves the plug from bar 3^c to next hole above and plugs it in connection with horizontal bar 1^a^x. The desired central office "B." is now signaled by pressing the key d of central office 75 "P." It will be seen that by pressing this key the bells y of the several central offices will be caused to ring by giving ground to the return portions of main-line circuit, which completes the circuit of the main-line battery A through the bell-relays. Each central office has a certain signal ascribed to it—say, for instance, the signal for "W." is one ring, for "B." two rings, and "P." three rings. The operator at "P." gives the "B." signal by pressing his key the 80 proper number of times. As soon as the operator of the "B." central office hears his signal, he opens his switch b to open the leading portion of the main-line circuit. He then removes the pin from the lower hole in upright-bar 3^b to the 85 next hole above, and plugs bar 3^b into connection with bar 1^a^x. The branch circuit of the return portion of the main line is now in connection with the earth at central office "B.," through secondary of transmitter T and telephone H. As soon as the operator at the "P." 90 signals "B.," he (the "P." central-office operator) closes his switches c⁴, opens his switch b⁹, and plugs his bar in the manner just described for central office "B.," and then the two central 95 offices are in circuit with each other through their branch circuits and a portion of the return of main-line circuit. The operator at "P." now tells the operator at "B." to get C¹¹. "B." central office operator now opens switch c⁴, removes the plug in bar 3^b one hole higher, and removes plug from bottom hole in bar 5^b to the 100 bar 1^a^x and signals C¹¹ by pushing key d at the "B." central station the proper number of times to sound the C¹¹ signal. Pushing this key 105 d the proper number of times gives the proper signal for station C¹¹ by giving ground to the return of said circuit. C¹¹ now hearing his signal, opens switch c and closes the transmitter-switches c' c², and listens through his telephone. He then responds "Hello" to operator at the "B." central office, and the latter informs him that he is wanted, and removes the plug in bar 5^b to the hole above and plugs bar 5^b in 110 connection with the same horizontal bar 2^a^x that he plugged bar 3^b with. Subscribers or individuals at C¹¹ and C¹⁷ are now in communication 115 with each other, their circuits being as follows: From ground at C¹⁷ station through the telephone and transmitter of said station- 120 switch c' to return portion of local line L⁴. The lead portion of this line having been opened by the opening of switch c, the circuit is necessarily through the return portion of bar 5^a at central office "P." through a portion 125 of horizontal bar 2^a^x into perpendicular bar 3^c, through branch S' of "P." central office to return portion of main line; through this into branch S of "B." central office, perpendicular bar 3^b; through a portion of horizontal bar 130 2^a^x into perpendicular bar 5^b; return of local circuit L⁴ to station C¹¹ through switch c² of

5 ³⁰ subscriber, his transmitter, and telephone to ground. It will thus be seen that all of the relays, signaling-magnets, and batteries are cut out of circuit while conversation is passing between two individual stations. By this arrangement the line is freed of much of the resistance which would tend otherwise to interfere with conversation between any two points of communication.

10 Transmitters and telephones as represented may be arranged according to any of the usual methods, so as to be looped into the return portion of the main-line circuit for the purpose of interviewing parties who are connected to 15 ascertain when they have finished talking, or for the purpose of giving instructions, &c.

It may be observed that the return portions of the local circuits, instead of returning through the several subscribers' instruments, 20 may be so run as to return direct to the central offices from which they started, and have branches extending from them to the several subscribers' instruments, and ground may be given to the return at any station by ground- 25 ing the branch either through the press-key or through the telephone and transmitter.

Having thus described my invention, what I claim as new, and desire to secure by Letters Patent, is—

1. A battery or generator, with one of its poles grounded and the circuit from the other forming a loop, (not grounded,) upon which is situated several stations, each with its signaling or controlling magnets situated in the leading portion of the loop, and provided with suitable means for opening and closing said portion of loop-circuit, and with suitable devices for giving ground to the return portions of the loop, either directly or through communicating-instruments, as and for the purpose set forth. 35

2. One or more generators and main line loop-circuits arranged as described, their stations being central offices, at each of which are situated several other generators with loop-circuits and stations extending therefrom, and means at each central office and station by which a circuit may be made up from parts of return portions of the main-line loop-circuit and any of the local loop-circuits, substantially as set forth. 40 45

In testimony whereof I affix my signature in presence of two witnesses.

CHARLES E. ALLEN.
